UNITED STATES PATENT OFFICE.

HOWARD M. DUDLEY, OF PHILADELPHIA, PENNSYLVANIA.

DYEING-MACHINE.

1,359,043.

Specification of Letters Patent. Patented Nov. 16, 1920.

Application filed December 9, 1919. Serial No. 343,685.

To all whom it may concern:

Be it known that I, HOWARD M. DUDLEY, a citizen of the United States, residing in the city of Philadelphia, in the county of 5 Philadelphia and State of Pennsylvania, have invented certain new and useful Improvements in Dyeing-Machines, of which the following is a full, clear, and exact specification.

10 My invention relates to dyeing devices and refers particularly to devices suitable for the dyeing of fibers in skein form.

The even and equal dyeing of yarn skeins is difficult to obtain in those devices in which 15 the skeins are subjected to the action of a circulation dyeing liquid. This result is due chiefly to the difficulty experienced in obtaining a uniform distribution of the dyeing liquid in all parts of the device at all 20 times.

The necessity of obtaining uniform distribution is increased in those cases which are now of most frequent occurrence in which the dye liquid consists of a number of 25 dyestuffs having different solubilities and different affinities for the fiber. Unless the distribution is absolutely uniform under these circumstances, the dyed results will be uneven and useless.

30 My device is constructed to overcome this particular difficulty and presents a means whereby the distribution of the dye liquid will be uniform throughout the entire dyeing chamber thus producing even and uniform dyed results.

In the accompanying drawings, illustrating one form of my device, similar parts are designated by similar numerals.

Figure 1 is a diagrammatic side plan view 40 of one form of the device of my invention.

Fig. 1^A is a broken view in the direction of the line 1^A of Fig. 1.

Fig. 2 is a vertical cross-section of the receptacle, dyeing chamber and contained 45 parts.

Fig. 3 is a section through the line 3—3 of Fig. 2.

Fig. 4 is a section through the line 4—4 of Fig. 3.

50 The particular form of the device of my invention, shown in the accompanying drawings, comprises a receptacle formed by the sides 10 and 11, the ends 12 and 13, the bottom 14 and the top 15. The sides 10 and 11 carry the angle irons 16, 16, 17, 17, and the ends 12 and 13 carry the angle irons

18, 18, 19, 19. Within the receptacle is a dyeing chamber formed by the sides 20, 20 supported by the angle irons 16, 16, 17, 17, and the ends 21, 21, supported by the angle 60 irons 18, 18, 19, 19. The bottom of the dyeing chamber is a foraminous member 22 attached to the sides 20, 20 and the ends 21, 21, the bottom 22 having a series of openings 23, 23. The top of the dyeing 65 chamber is a removable foraminous plate 24 similar to the bottom 23 and having a series of openings 25, 25. A foraminous plate 26, comprising a series of spaced parallel bars 27, 27 rests upon a flange 28 at the 70 lower extremities of the sides 10 and 11 and the ends 12 and 13. The plate 26 and the bottom 22 form a chamber 29. A foraminous plate 30, comprising a series of spaced parallel bars 31, 31 has an outwardly ex- 75 tended flange 32 capable of placement upon the tops of the sides 10 and 11 and the ends 12 and 13. The plate 30 and the top 15 form a chamber 33. The top 15 has the inwardly extended baffle-plate 34 and the 80 bottom 14 carries the member 35 with the baffle-plate 36.

A lower liquid chamber 37 is thus formed in the lower portion of the receptacle and an upper liquid chamber 38 is thus formed 85 in the upper portion of the receptacle. Pipes 39, 39 are contained in opposite sides of the lower liquid chamber 37 and pipes 40, 40 are contained in opposite sides of the upper liquid chamber 38. These pipes 39, 90 39, 40, 40 pass entirely through the liquid chambers 37 and 38 and have a series of openings 41, 41 in their upper portions throughout their entire length within the liquid chambers. One end of each of the 95 pipes 39, 39, 40, 40 is closed by a cap 42 fastened to the sides and ends of the receptacle by the screw bolts 43, 43, a tight joint being formed by the shipping box 44. Drain pipes 45, 45, each carrying a valve 100 45' act as a means for drawing the liquid from within the liquid chamber 37. A pipe 46 enters the liquid chamber 37 and a pipe 47 enters the liquid chamber 38.

Placeable within the dyeing chamber is a 105 skein holding device comprising upper side pieces 48, 48 and lower side pieces 49, 49, connected by the end pieces 50, 50. The end pieces 50, 50 contain a series of holes 51, 51, through which retaining pins can be 110 passed, the pins also passing through holes in the bottom pieces 49, 49, thus allowing of

- a change of distance between the top pieces 48, 48 and the bottom pieces 49, 49 to accommodate skeins of different lengths. The top pieces 48, 48 and the bottom pieces 49, 49 have a series of holes 52, 52 through which the skein sticks 53, 53 may be passed to support the skeins 100, 100. The top pieces 48, 48 are connected to the foraminous plate 30 by the links 54, 54.
- 10 Each of a series of members 55, 55 has an extended threaded bolt 56 capable of being screwed into holes in the upper plate 24 and the foraminous member 30. Each member 55 has a link 57, into which can be inserted 15 a broken link 58 attached to the top 15. The top 15 has a series of eye-bolts 59, 59 for purposes of removal.
- The pipes 46 and 47 are connected to the pipe 60 by means of the three-way cock 61, 20 the pipe 60 emptying into the reserve tank 62. A pipe 63, carrying the valve 64, connects the reserve tank 62 with the receiving ends of the rotary pumps 65 and 66. Each pipe 40 is connected to a pipe 67 by means 25 of stuffing boxes 68 and 69 and the two pipes 67, 67 converge into the pipe 70 which is connected to the pipe 71, carrying the valve 72, and connected with the delivery end of the pump 66.
- 30 Each pipe 39 is connected with a pipe 73. The two pipes 73, 73 converge into the pipe 74 which is connected to the pipe 75, carrying the valve 76 and connected with the delivery chamber of the pump 65. The pipe 35 71 is connected with the air pipe 77, carrying the valve 78 and the pipe 75 is connected with the air pipe 79 carrying the valve 80.
- A pipe 81, carrying the valve 82, passing 40 through one of the upper caps 42, enters the chamber of the testing device 83, corresponding to the chamber 38 of the larger device and a pipe 84, carrying the valve 85, passing through one of the lower caps 42, enters the chamber of the testing device 83, corresponding to chamber 37 of the larger device. The testing device 83 is exactly similar and proportionate to the larger receptacle and its contained parts.
- The operation of the device is as follows:—
- 50 The top 15 and the skein holding device are removed and skeins 100, 100 placed upon the rods 53, 53, the distance between the upper rods 53, 53 and the lower rods 53, 53 being such as not to cause a tension upon the fiber. The skein holding device is then attached to the member 30 and the member 30 and the plate 24 attached to each other by the screw bolts 56, 56, and the top 15 attached to the members 55, 55 by means of the links 58, 58 and the whole inserted within the dyeing chamber and the receptacle, the member 30 being supported to the sides and ends of the dyeing receptacle and the 65 top 15 resting upon the sides and ends of the

receptacle, to which it is attached by any suitable means.

Dye liquid is placed in the reserve tank 62 and all of the valves closed with the exception of valves 64, 76, 82 and 85 and the three-way cock is opened between the pipes 47 and 60 and the pump 65 started. The liquid thus passes from the reserve tank 62, through the pipe 63, the pump 65, the pipes 75, 74, 73 and 39, 39 into the lower liquid chamber, 37, whence it passes, after distribution by the baffle plate 36, through the foraminous plate 22, the chamber 29, the foraminous bottom 26, the dyeing chamber, the foraminous top 30, the chamber 33, the 80 foraminous member 24, the upper liquid chamber 38, the pipes 47 and 60 to the reserve tank 62 for continuous distribution. At the same time the liquid enters the testing device 83 through the pipe 84, passing upwardly through the members contained therein and through the pipe 81 to the liquid chamber 38.

When a reverse direction of the liquid is 90 desirous, valve 76 is closed, valve 72 is opened and the three-way cock 61 opened between the pipes 46 and 60. Pump 65 is stopped and pump 66 is started. The liquid is thus passed downwardly through the device in an opposite direction from that described above.

When it is desired to pass air through the device, the liquid is drained off and air forced through the pipes 77 and 79, thus causing it to pass through the device in 100 opposite directions, all of the valves being closed with the exception of valves 78, 80, 82 and 85.

It will thus be seen that by means of my device, the dye liquid is thoroughly mixed 105 in the reserve tank and is introduced into the receptacle through the perforated pipes 39 and 40 equally along two sides of the receptacle from which while being continuously mixed by baffle plates and foraminous members is introduced into the dyeing chamber for purposes of dyeing. By these means a uniform even treatment of the fiber is caused, resulting in even and uniform 110 dyeings.

I do not limit myself to the particular size, shape, number or arrangement of parts as described and shown, all of which may be varied without going beyond the scope of my invention as described, shown and 120 claimed.

What I claim is:—

1. In a dyeing machine, in combination, a receptacle, a dyeing chamber within the receptacle spaced from the sides thereof, a foraminous plate extending across the upper portion of the dyeing chamber, a foraminous plate extending across the lower portion of the dyeing chamber, a foraminous top to the dyeing chamber, a foraminous bottom 130

to the dyeing chamber, a plurality of removable rods within the dyeing chamber, a lower liquid chamber within the receptacle, a perforated pipe within the lower liquid 5 chamber, an upper liquid chamber within the receptacle, a perforated pipe within the upper liquid chamber and means whereby a liquid may be circulated in reverse directions through the perforated pipes and the 10 dyeing chamber.

2. In a dyeing machine, in combination, a receptacle, a dyeing chamber within the receptacle spaced from the sides thereof, a foraminous plate extending across the upper 15 portion of the dyeing chamber, a foraminous plate extending across the lower portion of the dyeing chamber, a foraminous top to the dyeing chamber, a foraminous bottom to the dyeing chamber, a removable 20 rod carrying member within the dyeing chamber, a plurality of upper and lower rods carried by the rod carrying member, a lower liquid chamber within the receptacle, a perforated pipe extending longitudinally within the lower liquid chamber, an upper liquid chamber within the receptacle, a perforated pipe extending longitudinally within the upper liquid chamber, a reserve tank, a conduit connecting the 25 lower liquid chamber with the reserve tank, a conduit connecting the upper liquid chamber with the reserve tank and means whereby a liquid may be passed continuously through the reserve tank and the dyeing 30 chamber in reverse directions.

3. In a dyeing machine, in combination, a receptacle, a dyeing chamber within the receptacle spaced from the sides thereof, a foraminous plate extending across the upper 35 portion of the dyeing chamber, a foraminous plate extending across the lower portion of the dyeing chamber, a foraminous top to the dyeing chamber, a foraminous bottom to the dyeing chamber, a removable 40 rod carrying member within the dyeing chamber, a plurality of upper and lower rods carried by the rod carrying member, a lower liquid chamber within the receptacle, a perforated pipe extending longitudinally within the lower liquid chamber, an upper liquid chamber within the receptacle, a perforated pipe extending longitudinally within the upper liquid chamber, a longitudinal baffle plate within the upper liquid 45 chamber, a longitudinal baffle plate within the lower liquid chamber, a reserve tank, a conduit connecting the lower liquid chamber with the reserve tank, a conduit connecting the upper liquid chamber with the reserve 50 tank and means whereby a liquid may be passed continuously through the reserve tank and the dyeing chamber in reverse directions.

4. In a dyeing machine, in combination, a 55 receptacle, a dyeing chamber within the re-

ceptacle spaced from the sides thereof, a foraminous plate extending across the upper portion of the dyeing chamber, a foraminous plate extending across the lower portion of the dyeing chamber, a foraminous top to the dyeing chamber, a foraminous bottom to the dyeing chamber, a plurality of removable rods within the dyeing chamber, a lower liquid chamber within the receptacle, a plurality of perforated pipes 70 within the lower liquid chamber, an upper liquid chamber, a plurality of perforated pipes within the upper liquid chamber, means whereby a liquid may be passed through the plurality of lower perforated 75 pipes and the dyeing chamber and means whereby a liquid may be passed through the plurality of upper perforated pipes and the dyeing chamber.

5. In a dyeing machine, in combination, a 80 receptacle, a dyeing chamber within the receptacle spaced from the sides thereof, a foraminous plate extending across the upper portion of the dyeing chamber, a foraminous plate extending across the lower portion of the dyeing chamber, a foraminous top to the dyeing chamber, a foraminous bottom to the dyeing chamber, a plurality of removable rods within the dyeing chamber, a lower liquid chamber within the receptacle, a plurality of perforated pipes extending longitudinally within the lower liquid chamber, an upper liquid chamber, a plurality of perforated pipes extending longitudinally within the upper liquid 85 chamber, a reserve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated 90 pipes and the dyeing chamber back to the reserve tank.

6. In a dyeing machine, in combination, a receptacle, a dyeing chamber within the receptacle spaced from the sides thereof, a foraminous plate extending across the upper portion of the dyeing chamber, a foraminous plate extending across the lower portion of the dyeing chamber, a foraminous top to the dyeing chamber, a foraminous bottom to the dyeing chamber, a plurality of removable rods within the dyeing chamber within the receptacle, a plurality of perforated pipes extending longitudinally within the lower liquid chamber, an upper liquid chamber, a plurality of perforated pipes extending longitudinally within the upper liquid chamber, a longitudinal baffle plate within the upper liquid chamber, a longitudinal baffle plate within the lower liquid chamber, a reserve tank and means whereby a liquid may be passed continuously through the reserve tank and the dyeing chamber in reverse directions.

7. In a dyeing machine, in combination, a 125 receptacle, a dyeing chamber within the re-

serve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated pipes and the dyeing chamber back to the reserve tank.

7. In a dyeing machine, in combination, a receptacle, a dyeing chamber within the receptacle spaced from the sides thereof, a 15 foraminous plate extending across the upper portion of the dyeing chamber, a foraminous plate extending across the lower portion of the dyeing chamber, a foraminous top to the dyeing chamber, a foraminous bottom 20 to the dyeing chamber, a removable rod carrying member within the dyeing chamber, a plurality of upper and lower rods carried by the rod carrying member, means whereby the removal of the top 25 foraminous plate will withdraw the rod-carrying member from within the dyeing chamber, a lower liquid chamber within the receptacle, a perforated pipe extending longitudinally within the lower liquid chamber, 30 an upper liquid chamber within the receptacle, a perforated pipe extending longitudinally within the upper liquid chamber, a reserve tank, a conduit connecting the lower liquid chamber with the reserve tank, a conduit 35 connecting the upper liquid chamber with the reserve tank and means whereby a liquid may be passed continuously through the reserve tank and the dyeing chamber in reverse directions.

40 8. In a dyeing machine, in combination, a receptacle, a dyeing chamber within the receptacle spaced from the sides thereof, a foraminous plate extending across the upper portion of the dyeing chamber, a foraminous 45 plate extending across the lower portion of the dyeing chamber, a foraminous top to the dyeing chamber, a foraminous bottom to the dyeing chamber, a removable rod carrying member within the dyeing chamber, a plurality 50 of upper and lower rods carried by the rod carrying member, a removable top to the receptacle, means whereby the removal of the receptacle top will withdraw the rod carrying member from within the dyeing chamber, a lower liquid chamber within the receptacle, a perforated pipe extending longitudinally within the lower liquid chamber, 55 an upper liquid chamber within the receptacle, a perforated pipe extending longitudinally within the upper liquid chamber, a reserve tank, a conduit connecting the lower liquid chamber with the reserve tank, a conduit 60 connecting the upper liquid chamber with the reserve tank and means whereby a liquid 65 may be passed continuously through the reserve tank and the dyeing chamber in reverse directions.

65 9. In a dyeing machine, in combination, a receptacle, a dyeing chamber within the

the reserve tank and the dyeing chamber in reverse directions.

9. In a dyeing machine, in combination, a receptacle, a dyeing chamber within the receptacle spaced from the sides thereof; a 70 foraminous plate extending across the upper portion of the dyeing chamber, a foraminous plate extending across the lower portion of the dyeing chamber, a foraminous top to the dyeing chamber, a foraminous bottom to the 75 dyeing chamber, a removable rod carrying member within the dyeing chamber, a plurality of upper and lower rods carried by the rod carrying member, means whereby the removal of the top foraminous plate will 80 withdraw the rod carrying member from within the dyeing chamber, a lower liquid chamber within the receptacle, a perforated pipe extending longitudinally within the lower liquid chamber, an upper liquid chamber 85 within the receptacle, a perforated pipe extending longitudinally within the upper liquid chamber, a longitudinal baffle plate within the upper liquid chamber, a longitudinal baffle plate within the lower liquid chamber, a reserve tank, a conduit connecting the lower liquid chamber with the 90 reserve tank, a conduit connecting the upper liquid chamber with the reserve tank and means whereby a liquid may be passed continuously through the reserve tank and the 95 dyeing chamber in reverse directions.

10. In a dyeing machine, in combination, a receptacle, a dyeing chamber within the receptacle spaced from the sides thereof, a 100 foraminous plate extending across the upper portion of the dyeing chamber, a foraminous plate extending across the lower portion of the dyeing chamber, a foraminous top to the dyeing chamber, a foraminous bottom to the 105 dyeing chamber, a removable rod carrying member within the dyeing chamber, a plurality of upper and lower rods carried by the rod carrying member, a removable top to the receptacle, means whereby the removal of the receptacle top will withdraw the rod carrying member from within the dyeing chamber, a lower liquid chamber within the receptacle, a perforated pipe extending longitudinally within the lower liquid chamber, 110 an upper liquid chamber within the receptacle, a perforated pipe extending longitudinally within the upper liquid chamber, a longitudinal baffle plate within the upper liquid chamber, a longitudinal baffle plate within the lower liquid chamber, a reserve tank, a conduit connecting the lower liquid chamber with the reserve tank, a conduit 115 connecting the upper liquid chamber with the reserve tank and means whereby a liquid may be passed continuously through the reserve tank and the dyeing chamber in reverse directions.

11. In a dyeing machine, in combination, a receptacle, a dyeing chamber within the 120

receptacle spaced from the sides thereof, a foraminous plate extending across the upper portion of the dyeing chamber, a foraminous plate extending across the lower portion of the dyeing chamber, a foraminous top to the dyeing chamber, a foraminous bottom to the dyeing chamber, a removable rod carrying member within the dyeing chamber, a plurality of upper and lower rods carried by the rod carrying member, a lower liquid chamber within the receptacle, a plurality of perforated pipes extending longitudinally within the lower liquid chamber, an upper liquid chamber, a plurality of perforated pipes extending longitudinally within the upper liquid chamber, a reserve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated pipes and the dyeing chamber back to the reserve tank.

12. In a dyeing machine, in combination, a receptacle, a dyeing chamber within the receptacle spaced from the sides thereof, a foraminous plate extending across the upper portion of the dyeing chamber, a foraminous plate extending across the lower portion of the dyeing chamber, a foraminous top to the dyeing chamber, a foraminous bottom to the dyeing chamber, a removable rod carrying member within the dyeing chamber, a plurality of upper and lower rods carried by the rod carrying member, means whereby the removal of the top foraminous plate will withdraw the rod carrying member from within the dyeing chamber, a lower liquid chamber within the receptacle, a plurality of perforated pipes extending longitudinally within the lower liquid chamber, an upper liquid chamber, a plurality of perforated pipes extending longitudinally within the upper liquid chamber, a reserve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated pipes and the dyeing chamber back to the reserve tank.

13. In a dyeing machine, in combination, a receptacle, a dyeing chamber within the receptacle spaced from the sides thereof, a foraminous plate extending across the upper portion of the dyeing chamber, a foraminous top to the dyeing chamber, a foraminous bottom to the dyeing chamber, a removable rod carrying member within the dyeing chamber, a plurality of upper and lower rods carried by the rod carrying member, a lower liquid chamber within the receptacle, a plurality of perforated pipes extending longitudinally within the lower liquid chamber, an upper liquid chamber, a plurality of perforated pipes extending longitudinally within the upper liquid chamber, a reserve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated pipes and the dyeing chamber back to the reserve tank.

portion of the dyeing chamber, a foraminous plate extending across the lower portion of the dyeing chamber, a foraminous top to the dyeing chamber, a foraminous bottom to the dyeing chamber, a removable rod carrying member within the dyeing chamber, a plurality of upper and lower rods carried by the rod carrying member, a removable top to the receptacle, means whereby the removal of the receptacle top will withdraw the rod carrying member from within the dyeing chamber, a lower liquid chamber within the receptacle, a plurality of perforated pipes extending longitudinally within the lower liquid chamber, an upper liquid chamber, a plurality of perforated pipes extending longitudinally within the upper liquid chamber, a reserve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated pipes and the dyeing chamber back to the reserve tank.

14. In a dyeing machine, in combination, a receptacle, a dyeing chamber within the receptacle spaced from the sides thereof, a foraminous plate extending across the upper portion of the dyeing chamber, a foraminous plate extending across the lower portion of the dyeing chamber, a foraminous top to the dyeing chamber, a foraminous bottom to the dyeing chamber, a removable rod carrying member within the dyeing chamber, a plurality of upper and lower rods carried by the rod carrying member, a lower liquid chamber within the receptacle, a plurality of perforated pipes extending longitudinally within the lower liquid chamber, an upper liquid chamber, a plurality of perforated pipes extending longitudinally within the upper liquid chamber, a longitudinal baffle plate within the upper liquid chamber, a longitudinal baffle plate within the lower liquid chamber, a reserve tank, a conduit connecting the lower liquid chamber with the reserve tank, a conduit connecting the upper liquid chamber with the reserve tank, means whereby a liquid may be passed from the reserve tank through the lower perforated pipes and the dyeing chamber back to the reserve tank and means whereby a liquid may be passed from the reserve tank through the upper perforated pipes and the dyeing chamber back to the reserve tank.

Signed at Chelsea, in the county of Suffolk and State of Massachusetts, this 15th day of November, 1919.

HOWARD M. DUDLEY.
